United States Patent

Des. 241,290

Patented Sept. 7, 1976

241,290

CHAIR

Ted A. Walker, Fresno, Calif.
(1320 N. Hunter, No. 8, Stockton, Calif. 95202)

Filed Mar. 31, 1975, Ser. No. 563,855

Term of patent 14 years

Int. Cl. D6—01

U.S. Cl. D6—73

FIG. 1 is a perspective view of a chair showing my new design.

FIG. 2 is a front elevation thereof.

FIG. 3 is a side elevation thereof, with the opposite side being identical to the side shown.

FIG. 4 is a rear elevation thereof.

FIG. 5 is a top plan view thereof.

FIG. 6 is a bottom plan view thereof.

I claim:

The ornamental design for a chair, as shown and described.
